UNITED STATES PATENT OFFICE.

ROBERT H. POSTLETHWAITE, OF SAN FRANCISCO, CALIFORNIA, ASSIGNOR
TO THE RISDON IRON AND LOCOMOTIVE WORKS, OF SAME PLACE.

DESIGN FOR A BEARING-BRACKET.

SPECIFICATION forming part of Design No. 28,160, dated January 11, 1898.

Application filed December 6, 1897. Serial No. 660,976. Term of patent 14 years.

To all whom it may concern:

Be it known that I, ROBERT H. POSTLETHWAITE, a subject of the Queen of Great Britain, residing in the city and county of San Francisco, State of California, have invented and produced a new and original Design for a Bearing-Bracket, of which the following is a specification, reference being had to the annexed drawing, showing the design in outline.

- 10 The bracket consists of a V-shaped frame B, which is united to a face or wall plate B'. This face or wall plate is cast with a forwardly-extending shoulder B², from which inwardly projects a flange C. The V-shaped frame is divided by the central horizontal plate C', so as to form a double triangular frame, each being provided with a strengthening-plate C². The face or wall plate B' and the forwardly-projecting shoulder B² have cast therewith
- 15 the bearing-box D, while at the apex of the V-shaped frame is formed the bearing-box D'. Bearing-boxes D and D' are arranged parallel and in the same horizontal plane and each is provided with a longitudinal shaft-opening a.
- 20 In the face or wall plate are formed the bolt-holes a', through which the fastening-bolts
- 25

extend. The edge of the projecting shoulder B² gradually curves outwardly from the point 1 of the face-plate toward the outer end of the bearing-box D and gradually inwardly from below the bearing-box toward the point 2 of the said face or wall plate.

The essential feature of the present design consists in a face or wall plate united to a V-shaped frame divided by a central plate or shelf into a double triangular frame, the face-plate having a forwardly-projecting shoulder and an inwardly-projecting flange, the whole supporting two parallel bearing-boxes in the same horizontal plane.

Having thus described my invention, what I claim as new, and desire to secure protection in by Design Letters Patent, is—

The design for a bearing-bracket substantially as shown and described.

In testimony whereof I affix my signature, in the presence of witnesses, this 30th day of October, 1897.

ROBERT H. POSTLETHWAITE.

In presence of—

N. A. ACKER,
LEE D. CRAIG.
